United States Patent Office

Des. 176,380
Patented Dec. 13, 1955

176,380

INSTRUMENT CLUSTER UNIT

Joseph R. Schemansky, Birmingham, Mich., assignor to
General Motors Corporation, Detroit, Mich., a corpo-
ration of Delaware

Application October 7, 1954, Serial No. 32,570

Term of patent 7 years

(Cl. D14—6)

Fig. 1 is a front elevational view of an instrument cluster unit showing my new design;

Fig. 2 is a section through the instrument cluster unit taken along the line 2—2 of Fig. 1; and

Fig. 3 is a reduced side elevational view of the instrument cluster unit.

I claim:

The ornamental design for an instrument cluster unit, substantially as shown.
